H. R. MURCHISON

LOCK FOR FILLER CAPS

Filed August 12, 1925

Inventor

Hugh R. Murchison,

By

Wray N. Hoffman

Attorney

UNITED STATES PATENT OFFICE.

HUGH R. MURCHISON, OF COLUMBIA, SOUTH CAROLINA.

LOCK FOR FILLER CAPS.

Application filed August 12, 1925. Serial No. 49,808.

To all whom it may concern:

Be it known that I, HUGH R. MURCHISON, a citizen of the United States, residing at Columbia, in the county of Richland and State of South Carolina, have invented new and useful Improvements in Locks for Filler Caps, of which the following is a specification.

This invention relates to locks for filler caps, and more particularly to locks for caps which are used to close the filling tubes of automobile radiators, gasoline tanks, and the like.

Various devices have been constructed for the purpose of preventing an unauthorized person from tampering with or removing the caps from radiators and gasoline tanks on automobiles, but they have not been found practical or commercially feasible due to the fact that they either necessitate the reorganization and design of the cap or nipple or both, or they are of such a character and design which makes them rather expensive in themselves and expensive to install.

Accordingly one of the objects of this invention resides in the production of a locking device of a character which is very simple, durable, and comprises very few parts.

Another object of this invention resides in the production of a locking device for filler caps which does not necessitate any change or reorganization in the design or make of the filling nipple.

The locking device constructed in accordance with my invention comprises a circular cap having a cylindrical boss extending inwardly from the exterior surface of the cap, a cylindrical lock casing comprising a rotary barrel and a lever mounted within said boss, and a cam surrounding said boss carrying a retaining means for example, a pair of pegs for the reception of the end of the lever therebetween, the movement of the lever causing a consequent movement of the cam into and out of contact with the inner periphery or face of the filler tube or nipple.

For the purposes of description, an embodiment of my invention is illustrated in the accompanying drawings, in which—

Figure 1 is a plan view of a filler cap provided with my invention.

Figure 2 is a sectional view taken on the line 2—2 of Fig. 1.

Figure 3 is a sectional view taken on the plane of line 3—3 of Fig. 2, having parts of the lock casing broken away.

Figure 4 is a detail view of the cam.

Referring to the drawings, reference numeral 1 represents the filling neck of a fuel tank for the delivery of fuel therethrough. The filling neck is provided with an external screw thread 2 adapted to receive the internally threaded cap 3. The cap 3 engages the external screw threads on the filling neck 65 1 in the ordinary manner. In order to have the cap 3 serve as an efficient seal for the tank I prefer to employ a washer or packing ring 4 as shown in Fig. 2.

The filler cap 3 is provided with an eccentrically disposed opening 5 for the reception of a cylindrical lock casing 6. The interior of the cap 3 is extended inwardly to form a cylindrical boss 8 within which is disposed the lock casing 6. Mounted about the circumference of the cylindrical boss 8 is a cam 9 carrying a pair of pegs 10 which is retained in position by the lock casing 17 attached to the end of the cylindrical boss 8 by means of fastening means 18 as screws or rivets as shown in Figs. 2 and 3. The lock casing 17 is provided with a slot 12, the purpose of which will be apparent from the description hereinafter set forth.

Mounted within the lock casing 6 is a rotary barrel 14 which is provided with a key-hole for the reception of a key 15. Disposed about the lower end of the rotary barrel 14 is a lever 11, one end of which is in engagement with a spring 13 carried by the base plate forming a part of the lock, and is operated by the key 15.

The lever 11 is in constant engagement with the pegs 10 of the cam 9, and as the lever 11 is moved either to the right or to the left by the key 15, so is the cam 9 correspondingly moved. The limit of movement of the cam is determined by the size of the slot or the portion of the lock casing 17 which is cut away to form such slot. The size of the slot which limits the movement of the cam with respect to the inner periphery or surface of the filling neck is clearly shown in Fig. 3. It is to be noted

that the size of this slot is not constant but must be varied to accommodate the different types of filling necks.

The device operates as follows:

5 After the cap has been secured or screwed on the filling neck, the key is manipulated to move the lever 11 and cam 9 with which it is in constant engagement to the dotted line position shown in Fig. 3 in which the 10 enlarged portion of the cam is pressed against the inner periphery or surface 16 of the filling neck 1. Now any attempted rotation of the cap to the left to remove it from the filling neck will tend to cause the 15 enlarged portion of the cam to wedge itself more forcibly against the surface 16; and thus make it impossible to unscrew the cap. When it is desired to remove the cap, the key is inserted and operated to retract the 20 cam 9 through the medium of the lever 11, whereupon the cam is returned to its full line position shown in Fig. 3, in which the cam 9 is free from the inner surface 16 of the filling neck 1, and offers no resistance to 25 the rotation of the cap.

From the foregoing description it will be apparent that a locking device made in accordance with the teachings of this invention comprises a very simple and durable 30 structure which can be manufactured commercially at a comparatively low cost, and which is adapted for any filling necks whether of the screw or other well known types.

35 Obviously, the invention is not limited to the specific embodiments thereof herein illustrated and described, but is capable of many variations and other applications within the spirit and scope of the invention as 40 set out in the appended claims.

Having thus described my invention, what

I claim as new and desire to secure by Letters Patent is:

1. A lock for filler caps comprising a locking cam mounted within the cap and 45 adapted to engage and bind against the inner surface of the filler nipple, and a key operated lever within said cap in constant engagement with said cam to move the cam into and out of contact with the inner face 50 of the filler nipple.

2. A lock for filler caps comprising a locking cam mounted within the cap and adapted to engage and bind against the inner surface of the filler nipple, and a lock 55 casing mounted within said cap and operable from the outside by a key and comprising a lever in operative engagement with said cam to move said cam into and out of operative relation with the filler nipple. 60

3. A lock for filler caps comprising a locking cam mounted within the cap and carrying a pair of pegs on its under side, and a lock casing mounted within the cap and having a horizontally disposed lever engaging the said pegs to move the cam into and out of contact with the inner face of the 65 filler nipple.

4. A lock for filler caps comprising the combination with the cap of a key operated 70 lock casing mounted within the cap and having a rotary barrel and a horizontally disposed lever carried by said barrel and having a cam in operative engagement with the lever adapted to cramp against the inner 75 face of the filler nipple, whereby when said lever is moved said cam will be forced into locking engagement with said face and the turning of the cap in a direction to remove the same will be prevented.

HUGH R. MURCHISON.
